US00D778247S

(12) **United States Design Patent** (10) **Patent No.:** **US D778,247 S**
Gurary et al. (45) **Date of Patent:** **** Feb. 7, 2017**

(54) **WAFER CARRIER WITH A MULTI-POCKET CONFIGURATION**

(71) Applicant: **Veeco Instruments, Inc.**, Plainview, NY (US)

(72) Inventors: **Alexander Gurary**, Bridgewater, NJ (US); **Mandar Deshpande**, Bridgewater, NJ (US); **Aniruddh Parekh**, Milburn, NJ (US); **Yuliy Rashkovsky**, New York, NY (US)

(73) Assignee: **Veeco Instruments Inc.**, Plainview, NY (US)

(**) Term: **14 Years**

(21) Appl. No.: **29/524,104**

(22) Filed: **Apr. 16, 2015**

(51) **LOC (10) Cl.** **13-03**

(57) **CLAIM**

We claim the ornamental design for a wafer carrier with a multi-pocket configuration, as shown and described.

DESCRIPTION

FIG. 1 is a perspective view of a wafer carrier with a multi-pocket configuration according to the new design.

FIG. 2 is a top plan view of the wafer carrier with a multi-pocket configuration shown in FIG. 1.

FIG. 3 is a detail view of a portion of the wafer carrier with a multi-pocket configuration shown in FIG. 1 detailing an enlarged portion corresponding to the area indicated in FIG. 1 that includes a single pocket and surrounding region in a perspective view.

FIG. 4 is a right side view of a wafer carrier with a multi-pocket configuration according to the new design shown in FIG. 1, with the left side, front, and rear views being the same as the right side view; and,

FIG. 5 is a bottom plan view of a wafer carrier with a multi-pocket configuration according to the new design shown in FIG. 1.

The broken lines, where present, in FIGS. 1, 3, 4 & 5 illustrate portions of the wafer carrier with a multi-pocket configuration that represent environment of the claimed design and form no part of the claimed design. The dash-dot lines of FIG. 1 define the area corresponding to the enlarged portion shown in FIG. 3 and form no part of the claimed design. The dash-dot and broken lines in FIG. 3 represent the edge of the enlarged portion of the design and form no part of the claimed design.
